UNITED STATES PATENT OFFICE.

JULIAN O. ELLINGER, OF NEW YORK, N. Y.

MANUFACTURE OF SECONDARY-BATTERY PLATES.

SPECIFICATION forming part of Letters Patent No. 388,960, dated September 4, 1888.

Application filed April 30, 1887. Serial No. 236,625. (No model.)

To all whom it may concern:

Be it known that I, JULIAN O. ELLINGER, of the city of New York, in the county and State of New York, have invented a certain 5 new and useful Improvement in the Manufacture of Secondary-Battery Plates, of which the following is a specification.

The object of my invention is to provide secondary-battery plates of an efficient character and by a simple and convenient process, including the application of pressure, to consolidate the metal of the plates and increase the efficiency thereof, as set forth in my application filed April 23, 1887, Serial No. 235,919.

15 The plates produced by my method are of the form which has been found best in practice—namely, a plate of lead or an alloy of lead and other metal, provided with apertures extending through it, such apertures having 20 opposite bevels, so as to have a greater width at one point than at another, whereby the active material placed in such apertures is held from falling out.

25 The present invention consists, mainly, in stamping out by cutting and pressing from a sheet of metal two similar plates, each having beveled apertures, and attaching such plates together, so that a single plate with oppositely-beveled apertures is formed.

30 The pressing of the plate is a feature of great advantage in the manufacture of secondary-battery plates, since it consolidates the metal and makes it more homogeneous, eliminates any air-holes, and makes a plate of even 35 density and conductivity, the conductivity and electrical capacity being increased without increase in the weight and with a decrease in bulk for the same weight. The plate is also made harder and stronger by pressing and 40 the spaces between the holes may be made very narrow. By my invention, therefore, I not only provide a simple and cheap process of making the plates, but I also improve the construction and increase the efficiency and 45 usefulness of such plates.

My invention is illustrated in the accompanying drawings.

Figure 1 is a view in elevation of a plate made according to my invention in the preferred form; Fig. 2, an enlarged cross-section 50 of a part of said plate; Fig. 3, a section of the

double plate with its parts united so that the bevels are in the opposite direction from those of Figs. 1 and 2; Fig. 4, a section of the die-plates used for cutting and pressing the half-plate at one operation; Fig. 5, a section of die-plates used for cutting the apertures only, and Fig. 6 a section of die-plates used to press the apertures into form. 55

The completed plate in its preferred form 60 consists of two rectangular half-plates, A and A', each formed with beveled edges *a* and with beveled apertures *b*, the plates being united together at their edges, as shown in Fig. 2, so that a plate is formed with apertures having 65 opposite bevels and narrowest at their middle part. The plates are preferably united by fusion; but they may be bolted or riveted or otherwise secured together. The plates may, however, be put together in the opposite way, 70 as in Fig. 3, so that the apertures are widest at the middle and narrower at the surfaces of the complete plate. It will be understood that in either form the irregularity in shape of the aperture prevents the active material from 75 falling out on either side.

In forming the plates I may use the die-plates B B' shown in Fig. 4. The upper die-plate B has parallel rows of beveled projections *d*, each having a recess tapering at its 80 inner end. The lower die-plate B' has square projections *e* and recesses *f* between them. The die-plate B preferably has cutting-edges at *g*.

A sheet of metal of proper thickness to form 85 one of the half-plates—the two half-plates being exactly alike—is placed between these die-plates, and they are brought together upon it by means of a suitable press or otherwise, whereby the projections of the upper plate 90 enter the recesses *f* of the lower plate, and the cutting-edges of said projections cut out portions of the metal, which fall through said recesses. At the same time the remaining metal parts of the plate are forced by the projections 95 *e* up into the tapered ends of the recesses of the upper plate, whereby such metal portions are pressed into the desired beveled form, the metal is consolidated, and the metal between the holes is brought to the narrowest possible 100 edges. At the same time the cutting-edges at *g* cut out the plate from the metal sheet. The

die-plates may also be formed so as to cut the tongue *h* for making connection to the plate. The half-plates may also be formed by first cutting and then pressing, as illustrated in Figs. 5 and 6. The lower die-plate *C* of Fig. 5 is like the lower one of Fig. 4, and also the upper plate *C* is the same as the upper plate of Fig. 4, except that the inner ends of its recesses are square instead of tapering. The cutting-edges of the upper dies pass through the sheet of metal and cut square apertures therein. The sheet thus perforated is then placed between the pressing die-plates *D D'*, Fig. 6, the lower one having square projections and the upper one recesses with beveled or tapering inner ends. On these dies being brought together upon the perforated metal the metal between the perforations is forced into the recesses in the upper die and pressed and consolidated into the beveled form shown. Two of these beveled plates are, as already stated, placed together, as in Fig. 2 or Fig. 3, and joined together at their edges, forming a complete plate of compact and consolidated metal and with the metal brought to such narrow edges between the apertures that when the apertures are filled with the active material the plate has practically no inactive metal surface.

What I claim is—

1. The method of making a secondary-battery plate, consisting in forming two half-plates by pressing the metal into the desired form and then securing them together, substantially as set forth. 30

2. The method of making a perforated secondary-battery plate, consisting in forming two perforated half-plates by cutting and pressing and then securing them together, substantially as set forth. 35

3. The method of making a perforated secondary-battery plate by stamping two half-plates with beveled apertures, and then securing said plates together, substantially as set forth. 40

4. The method of making a perforated secondary-battery plate, consisting in forming two half-plates by first cutting apertures in metal sheets and then pressing such apertures into the desired form and securing said half-plates together, substantially as set forth. 45 50

This specification signed and witnessed this 28th day of April, 1887.

JULIAN O. ELLINGER.
